(57) **CLAIM**

The ornamental design for a peace fish shaped carabiner, as shown and described.

DESCRIPTION

FIG. 1 is a plan view of the top and bottom sides, which are mirror images, of my new design for a peace fish shaped carabiner.

FIG. 2 is a front plan view of the carabiner shown in FIG. 1.

FIG. 3 is a rear side plan view of the carabiner shown in FIG. 1.

FIG. 4 is a right side plan view of the carabiner shown in FIG. 1.

FIG. 5 is a left side plan view of the carabiner shown in FIG. 1.

FIG. 6 is a top perspective view of the carabiner shown in FIG. 1.

FIG. 7 is a plan view of the top and bottom sides, which are mirror images, alternate embodiment of the carabiner shown in FIG. 1 made with round wire.

FIG. 8 is a front plan view of the carabiner shown in FIG. 7.

FIG. 9 is a rear side plan view of the carabiner shown in FIG. 7.

FIG. 10 is a right side plan view of the carabiner shown in FIG. 7.

FIG. 11 is a left side plan view of the carabiner shown in FIG. 7; and,

FIG. 12 is a top perspective view of the carabiner shown in FIG. 7.
